OSCAR L. OWEN, OF WHITINSVILLE, MASSACHUSETTS, ASSIGNOR TO THE WHITIN MACHINE WORKS, INCORPORATED, OF WHITINSVILLE, MASSACHUSETTS.

STOP-MOTION FOR COMBING-MACHINES.

SPECIFICATION forming part of Letters Patent No. 737,268, dated August 25, 1903.

Application filed September 19, 1902. Serial No. 124,016. (No model.)

To all whom it may concern:

Be it known that I, OSCAR L. OWEN, a citizen of the United States, residing at Whitinsville, in the county of Worcester and State of

5 Massachusetts, have invented a new and useful Improvement in Stop-Motions for Combing-Machines, of which the following is a specification.

This invention has reference to an improvement in machines for combing cotton and similar textile fiber. In this class of combing-machines the prepared sliver is delivered to the combing mechanism by a pair of feed-rolls, the lower one of which is positively 10 driven, the upper roll being held against the driven roll by spring-pressed arms. The feed-rolls are necessarily located in a confined 15 space above the cushion-plate. In this class of machines the sliver is liable to wind on the lower or driven feed-roll and prevent the delivery of the sliver to the combing mechanism, thereby diminishing the product of the machine. The coiling and packing of the sliver between the lower feed-roll and the 20 parts adjacent thereto exert at times such pressure on the cushion-plate as to destroy the same and make expensive repairs necessary.

The object of this invention is to arrest the rotation of the lower feed-roll as soon as possible 25 after the delivery of the sliver is interrupted by the winding of the sliver on the feed-roll; and to this end the invention consists in the peculiar and novel construction and combination of mechanism whereby the driven feed-roll may be automatically disconnected 30 from the driving-gear, as will be more fully set forth hereinafter.

Figure 1 is a view, partly in section, taken 35 transversely through one of the sections of a combing-machine, showing the feed-rolls and the safety attachment connected with the same. Fig. 2 is a longitudinal skeleton view 40 showing the feed-rolls, the gears for driving the lower feed-roll, and the safety attachment connected with the driven feed-roll. Fig. 3 is an end view, partly in section, showing the 45 positions of the safety attachment in broken lines with the driven feed-roll partly raised and in solid lines when the driven feed-roll 50 is raised sufficient to disengage the driving

mechanism. Fig. 4 is a transverse sectional view of the feed-rolls, the cushion-plate, and the supporting-bar adjacent to the driven feed-roll.

In the drawings, *a* indicates the end frames of a section of a combing-machine; *b*, the driven feed-roll; *c*, the top roll; *a'*, the journal-bearings for a driven feed-roll, (these bearings usually supporting only the lower half of the driven feed-roll shaft,) and *a²*, the bar on 55 which the cushion-plate *a³* is supported. One of the journal-bearings *a'* has the extension *a⁴* provided with the notches *a⁵* and *a⁶*, and on the driven feed-roll *b*, above the extension *a⁴*, is placed the collar *a⁷*, having the pawl *a⁸*, 60 projecting from one end, formed to engage with the notches *a⁵* and *a⁶*. To the collar *a⁷* is connected the counterweight *a⁹*. The collar *a⁷* is free to turn on the driven feed-roll 65 shaft; but in the normal condition the pawl of the collar bears on the extension *a⁴* and supports the counterweight *a⁹* in the raised 70 position. On the shaft of the driven feed-roll *b*, near its end, is secured the gear *b'*, which 75 engages with the driven pinion *b²*, by which in the normal condition rotary motion is imparted to the feed-roll.

The top roll *c* is journaled in the arms *c'*, pivotally secured to the frames *a a*. The arms *c' c'* are provided with the studs *c² c²*, 80 on which the coiled tension-springs *c³* are supported, the opposite ends of these springs being adjustably secured to the brackets *c⁴*. By this construction the top roll is free to ride on the driven feed-roll resisted by the 85 strains exerted by the coiled springs *c³ c³*.

In the normal operation of the machine the sliver *d* is usually delivered in the form of a lap of a width corresponding with the length of the feed-rolls. It is usually carried from 90 the lap-roll *d'* by means of a guide between the feed-rolls and is delivered in the normal condition to the combing mechanism. When now the sliver laps around the feed-roll, the sliver will be crowded between the bar *a²* and 95 the cushion-plate so quickly and so tight that frequently these parts, and particularly the cushion-plate, are broken.

By the use of my stop-motion the counter-weight *a⁹* somewhat counteracts the tension 100

of the coiled springs c^3 , so that when the sliver laps around the feed-roll and causes the driven feed-roll to rise in its journal-bearings the counterweight a^9 causes the pawl a^8 to engage first with the notch a^6 and then with the notch a^5 , thereby lifting the shaft of the driven feed-roll and disengaging the gear b' from the pinion b^2 to stop the machine before the continual winding of the lap around the feed-roll can break or injure the parts adjoining the same.

Having thus described my invention, I claim as new and desire to secure by Letters Patent—

15 1. In a machine for combing cotton or similar textile fiber, the combination with the driven feed-roll and the mechanism for driving the feed-roll, of means for disconnecting the driven feed-roll from the driving mechanism, as described.

20 2. In a machine for combing cotton or similar textile fibers, the combination with the driven feed-roll and the journal-support for the same, of a weighted collar and a pawl on the collar adapted to support the feed-roll out of engagement with the driving mechanism, as described.

25 3. A stop-motion for combing-machines, consisting of an overweighted pawl connected

with the driven feed-roll, whereby the feed- 30 roll may be disconnected from the driving mechanism, as described.

4. In a combing-machine of the nature described, the combination with the driven feed-roll, the parts adjacent to the driven feed-roll, and the driving mechanism, of a stop mechanism coöperating with the shaft of the feed-roll to disconnect the driving mechanism from the feed-roll, as described.

5. The combination in a combing-machine 40 of the nature described with the feed-roll b , the journal-bearings a' for the same, the pinion b^3 and the gear b' , of the extension a^4 , having notches a^5 and a^6 on the same, the collar a^7 supported on the shaft of the feed-roll, the pawl a^8 on the collar and the counterweight a^9 connected with the collar, whereby on the lapping of the sliver around the feed-roll the gear b' may be automatically disconnected from the driving-pinion b^3 , as de- 45 scribed.

In testimony whereof I have signed my name to this specification in the presence of two subscribing witnesses.

OSCAR L. OWEN.
